ELECTROPLATING MACHINE

Albert H. Hannon, Springfield, Ohio

Application March 13, 1931, Serial No. 522,267

11 Claims. (Cl. 204—5)

This invention relates to improvements in electroplating machines wherein the pieces of work or objects being plated are carried along from one tank to the next and automatically raised and lowered to lift the work out of one tank and lower it into the next tank, electric current being supplied in one or more of the tanks for depositing the plate.

Since such apparatus requires a number of the tanks for the various operations of cleaning, washing, plating and the like, and since in an automatic conveyor plating machine the time for each different treatment is governed by the length of the particular tank, because the conveying mechanism travels at the same speed in moving along each of the tanks and the total length of the tanks becomes quite great, objects of this invention are to provide a simplified form of machine in which the tanks are arranged in two adjacent rows so that the length of the machine is shortened, and so that the work is returned to the same place at which it started.

In the plating machines generally in use, the conveying mechanism and the transfer mechanism are usually separate devices, and the transfer devices pick the work-support racks off from the conveyor, which moves steadily in a horizontal plane, lifts the work up and deposits the work in the next tank at about the same position on the conveyor. In such machines the movement of the transfer arms must be synchronized with the movement of the conveyor and in relation to the supporting elements on the conveyor, therefore changes in the spacings between the successive work supports for different widths of work cannot be readily made.

In this invention the carrier arms are pivoted to an endless chain which operates in a horizontal plane around a frame placed between the rows of tanks. The arms overhang the tanks and are raised and lowered by cams attached to the sides of the frame as the arms are moved along over the ends of the tanks. In a specific machine built according to this invention the pitch or spacing of the carrier arms can be varied in any multiples of six inches without making any changes in the timing because each arm is lifted as it moves into relation with the cams, which can be fixed as desired along the frame, and where the spacing is close several arms may be being lifted or lowered by the same cam.

The construction of the machine becomes comparatively simple because it is only necessary to drive the conveyor chain. Also the spacing of the arms does not change as they are being

lifted. In other machines while one rack is raised the next rack is moving up, while in this invention there is no crowding together as the forward movement of the racks is continuous and the spacing remains the same. This permits of the minimum spacing of about four inches between the work, which is requisite for the plating. In this invention it is not uncommon to have as many as fifty arms in one tank at the same time, and, for example, racks twenty inches in width can be spaced at twenty four inch intervals, while in other machines the intervals would have to be much greater. With the usual conveyor speed of about six feet a minute the lift being about three feet, and the transfer speed being about four times the speed of the conveyor, the conveyor would move about nine inches in the other machines while a rack was being lifted out of a tank. This would require at least ten inches of clear space between the racks, and about thirty inch intervals in the spacing of the racks. Then with fifty racks in one tank the tank would necessarily be twenty five feet longer than would be necessary in this invention.

Other advantages of this invention are that the tanks are accessible. This is of importance because chemicals must be added to the solutions daily and new anodes hung in the tanks periodically.

Also the machine can be both loaded and unloaded at one place so that one operator can run the machine, and the mechanism is surrounded by the tanks and the operator is protected and not exposed to danger from contact with chains, gears or other moving parts.

An illustrative embodiment of this invention is shown in the accompanying drawings, in which:

Fig. 1 is a plan view of a machine with mid portions broken out.

Fig. 2 is a side elevation of the same.

Fig. 3 is a cross section on substantially the line 3—3 of Fig. 2.

Fig. 4 and Fig. 5 placed end to end constitute a diagram of the arrangement of a complete plating machine.

Fig. 6 is a plan view of one of the carrier arms, and shows a fragment of the side of the support frame.

Fig. 7 is a plan view of a portion of the chain belt.

Fig. 8 is a detail section on the line 8—8 of Fig. 6.

Fig. 9 is an elevation of the end of the carrier arm.

Fig. 10 is a cross section on the line 10-10 of Fig. 1.

Fig. 11 is a section on the line 11-11 of Fig. 1, and shows a modification in the form of the carrier arm.

Fig. 12 is a side elevation of the parts shown in Fig. 11.

The machine comprises two spaced rows A and B of plating and solution tanks joined at the ends by circular tanks C and D. A complete arrangement of the tanks is shown in Fig. 4 and Fig. 5 and their functions indicated by the legends thereon so that the problems involved in plating machines can be perceived. A gap E is provided between the tanks at one side for the loading and unloading.

Between the two rows of tanks is a frame structure comprising the spaced channel section vertical support columns 11 and 12 which are connected at the upper ends, at each side, by the horizontally disposed channel section beams 13 and 14, secured to the flanges of the columns; and rotatably supported on the ends of the horizontal members are provided the horizontally disposed sprocket wheels 15 and 16.

The sprocket wheel 15, at the feed end of the machine, is rotatably mounted in a motor bed plate 17 which is slidably mounted on the transverse I-beams 18 and 19, bolted on the tops of the longitudinal frame members 13 and 14. The bed plate is adjusted in position by means of a screw 20, which is threaded through an anchor bracket 21 secured to the transverse member 19. The opposite sprocket wheel 16 is rotatably mounted in a bearing 22 which is fixedly mounted on the transverse I-beam 23, bolted to the tops of the longitudinal members.

Mounted on the sprocket wheel and extending along the outer sides of the channel members 13 and 14 and between the flanges thereof is an endless chain belt 24 composed of spaced rollers 25 and inner and outer pairs of side connecting links 26 and 27. On the bed plate is mounted the motor 28, which is connected for driving the sprocket wheel 15 through the speed reducer 29, worm 30 and worm wheel 31, keyed to the shaft 32 of the sprocket wheel. In operation the chain is continuously driven in a counter-clockwise movement, as viewed in Fig. 1; and the reaches 30 of the chains are guided, laterally, along the outer sides of the frame members 13 and 14 between the web of said members and the depending flange of an angle iron 34 secured on the top of the side frame members.

At intervals in the chain one of the lower links is replaced by an attachment plate 35 to which is bolted a carrier arm bracket 36. The bracket has two vertical spaced lugs 37, and projecting inwardly is a lug portion 38 on the inner end of which is rotatably mounted a supporting roller 39. On the upper surface of the bracket is provided a pad 40 for engaging with the under surface of the projecting portion of the plate 35, and on the upper surface of said portion of the plate, directly opposite the pad, is bolted a short angle iron 41 for engaging the outer surface of the depending flange of the member 34, the upstanding flange of the angle iron 34 being directly opposite to two of the adjacent chain rollers 25, as best shown in Fig. 6, so that the bracket is firmly guided in the horizontal plane as it is moved along by the chain. The angle member 41 and the bracket are removably secured to the attachment plate 35 by means of cap screws 42, which extend through the horizontal flange of the angle

41 and the plate 35 and thread into the pad portion 40 of the bracket. Thus on a three inch pitch chain the attachment plates 35 are provided at six inch intervals, and the brackets may be readily attached to the chain at six inch intervals or multiples thereof as may be desired.

Along the two sides of the frame, the supporting rollers 39 ride on the projecting flange 45 of the angle sectioned guide rails 46 secured to the outer side of the web of the side member 13, and likewise to the opposite side member 14, a lip 47 being provided at the outer edges of the flanges 45 to prevent the possibility of the roller 39 slipping off from the flange.

The work support members 48 are pivotally attached to the brackets and insulated therefrom. These members are in the form of a bell-crank, having a depending arm 49 and an outwardly projecting arm 50, the arms being joined to a hub 51 which is inserted between the lugs 37 and 40 pivotally secured thereto by means of a horizontally disposed pin 52, suitable insulation 53 is provided around the pin and between the sides of the hub and the lugs 37 of the bracket, as shown in Fig. 8, and on the projecting ends of 25 the pins are pinned the collars 54 and 55.

On the lower end of the arm 49 is rotatably mounted an insulated roller 56 which rides against a cam track 57 mounted on each side of the frame for rotationally supporting the member 48; and 30 at intervals along the sides of the frame, at the ends of the tanks, are mounted the outwardly and upwardly projecting arcuate cams 58. These cams are thus inserted in the track 57 and form a portion thereof for raising and lowering the arm 35 members 48 as the members pass the ends of the tanks.

To each of the outwardly projecting arms 50 is bolted an extension bar 60 which projects over the tanks, and at the outer end is provided with a bifurcated hook 61. A rod 62 is inserted in the hook and the hooked end 63 of the work rack 64 is hung on the rod, so that the rack is freely suspended from the end of the bar 60.

In the plating tanks the usual anode rods 65 are fixedly mounted and on which are hung the anodes, not shown. The cathode connection is made to the bus bar 66 which is yieldably mounted on the outer side of the frame, as best shown in Fig. 10. Then on the inner side of the arm 50 portion 49 is provided a projecting portion 67 which slidably engages with the surface of the bus bar 66 when the work support arm is lowered position, so that the plating current flows from the anode bar 65 through the solution in 55 the tank to the work, and then through the carrier arm to the cathode bus bar 66 while the work is in the tank. As soon as the work is lifted the connection to the bus bar 66 is broken.

In Figs. 11 and 12 is shown an arrangement 60 whereby two racks of work can be hung side by side on each carrier arm so that the capacity of the machine can be doubled for small pieces of work. To the arm 50 is bolted a bar 70 having an upwardly curved arcuate portion 71. On the outer end of the bar is pivotally mounted a yoke 72 having forked hooks 73 and 74 at the ends thereof. At the middle the yoke has two spaced upwardly projecting arms 75 and 76, between which is inserted the ends of the bar 70, the yoke being secured to the end of the bar by the pin 77. Then to prevent the yoke from swinging and hold the same parallel as the arm is raised or lowered, a rod 78 is provided which is pivotally mounted in parallel relation to the 75

lower arm 70. At the outer end, the rod 78 is pivotally secured between the upper ends of the yoke arms 75 and 76 by the pin 79; and at the inner end the rod is pivotally connected by a pin 80 to a bracket 81. The bracket 81 is insulatedly mounted on the angle 41, and, since the carrier arm portion 48 is also insulated, the frame and conveyor mechanism is protected from stray current, the negative connection being made to the cathode bus bar 66, as described above. By curving the bar 70 and rod 78 the yoke can be raised the full distance without having it strike against the bar, see Fig. 11; and the rod 78 has an angular formation at 82 to provide clearance for the mechanism at the end of the frame.

Around the ends of the frame the cam track has an arcuate portion 83 for supporting the rollers 56, the support for the rollers 39 not being required because the chain is then engaged on the teeth of the sprocket wheels.

Having thus described my invention, I claim:

1. In an electroplating machine, a tank, a horizontal conveyor frame extending along the side of the tank, a bracket slidably guided and supported on the side of the frame, the frame and bracket being disposed entirely at one side of the tank, a work support arm pivotally mounted on the bracket and extending over the tank, and a cam track mounted on the side of the frame for supporting the arm as it is carried along the tank, and for raising and lowering the arm as it is carried over the ends of the tank.

2. In an electroplating machine, a tank, a frame extending alongside the tank, guide rails mounted on the side of the frame, a bracket slidably mounted on the rails, means for moving the bracket along the rails, a work support arm pivoted to the bracket to swing in a plane transverse to the movement thereof, and a track mounted on the side of the frame for supporting the arm in a position extending out over the tank as the arm is carried along the length of the tank, and a cam forming a continuation of the track for raising and lowering the arm as it is carried past the ends of the tank.

3. In an electroplating machine, a double row of solution tanks, a support frame positioned between the rows of tanks, horizontally disposed sprocket wheels rotatably mounted on the ends of the frame, means for rotating one of said wheels, a chain belt supported on the sprocket wheels and extending along the sides of the frame, lateral guides for the chain mounted on the sides of the frame, a bracket dependingly attached to the chain, rails mounted on the sides of the frame for slidably supporting the bracket, a work support arm pivotally mounted on the bracket for movement in a plane at right angles to the chain, and tracks mounted on the sides of the frame for supporting the arm at an elevation projecting over the tanks, said tracks having projecting portions for raising and lowering the arm as the bracket is moved past the ends of the tanks.

4. In an electroplating machine, a double row of solution tanks, a support frame positioned and disposed entirely between the rows of tanks, sprocket wheels rotatably mounted on the ends of the frame, means for rotating one of said wheels, a chain belt supported on the sprocket wheels and extending along the sides of the frame, a bracket dependingly attached to the chain, rails mounted on the sides of the frame for slidably supporting the bracket, an insulated work support arm pivotally mounted on the bracket in a

plane transverse to the movement of the bracket, tracks mounted on the sides of the frame for supporting the arm at an elevation projecting over the tanks, and cams for raising and lowering the arm to carry the work into and out of the tanks as the bracket is carried along on the chain past the ends of the tanks, and bus bars yieldingly mounted on the sides of the frame for contacting with the arm in lowered position for connecting an electrical source thereto.

5. In an electroplating machine, an endless chain supported in a horizontal plane, means for driving the chain, a bracket dependingly attached to the chain, a rail for slidably supporting the bracket, a work support arm pivoted to the bracket, in a plane transverse to the movement of the bracket, a track for supporting the arm in an elevated position as it is moved along, and cams interposed in the track for raising and lowering the arms at predetermined locations.

6. In an electroplating machine, a solution tank, an endless chain belt supported to travel in a horizontal plane and disposed entirely at one side of the tank, lateral guides for the reaches of the chain, a bracket attached to the chain, a rail for slidably supporting the bracket, an insulated work support arm pivotally connected to the bracket for swinging transverse to the movement of the chain, means for supporting the arm partially elevated and projecting outwardly from the chain as it is moved horizontally, means at predetermined positions for raising and lowering the arm, and means for supplying an electric current to the arm.

7. In an electroplating machine, an endless chain belt supported to travel in a horizontal plane, lateral guides for the reaches of the chain, a bracket attached to the chain, a rail for supporting the bracket, an insulated work carrying arm pivotally connected to the bracket and slidably supported to project outwardly from the chain, a cam for raising and lowering the arm, and means slidably contacting with the arm in lowered position for supplying electric current thereto.

8. In an electroplating machine, an insulated pivotally mounted arm for carrying the work in the plating tanks, means for moving the arm along the tanks, means for raising and lowering the arm as it is moved along, a yoke for supporting the work pivotally mounted on the end of the arm, and an insulated arm pivotally mounted and pivoted to the yoke in parallel relation to said arm for maintaining the yoke in an upright position.

9. In an electroplating machine, a tank, a bracket slidably supported and moved along at one side of the tank, a cantilever arm pivoted to the bracket and overhanging the tank, a work-support yoke pivotally mounted on the end of the arm, means for raising and lowering the arm as it is moved along to carry the work into and out of the tank, and an arm pivotally connected to the bracket and to the yoke in parallel relation with said arm for maintaining the yoke in an upright position.

10. In an electroplating machine, a horizontal conveyor, a work support arm pivoted to the conveyor for rotation at right angles to the movement of the conveyor, the arm having a downwardly projecting bell crank rigid therewith, a track parallel to the movement of the conveyor for slidably supporting the bell crank as it is moved along the same to maintain the bell crank in a partially elevated position projecting from

the side of the conveyor, and means forming interruptions in the track for slidably contacting with the bell crank for rotating the arm to raise and lower the arm as the arm is moved past said means.

11. In an electroplating machine, a horizontally disposed conveyor chain, means for continuously moving the chain, a work support arm pivoted to the chain for rotation at right angles to the movement of the same, the arm having a

bell crank lever rigid therewith, a track fixedly mounted parallel to the movement of the chain slidably contacted by the lever to support the arm in a partially elevated position projecting at one side from the chain, and means interrupting the track for slidably contacting with the lever to raise and lower the arm as the arm is moved past said means.

ALBERT H. HANNON. 10
